ATTORNEY'S.

UNITED STATES PATENT OFFICE.

CHESTER B. ROSENBURGH, OF ROME, NEW YORK, ASSIGNOR OF ONE-HALF
TO THE ROME HAME COMPANY, OF SAME PLACE.

DESIGN FOR A HAME-STAPLE.

SPECIFICATION forming part of Design No. 25,968, dated August 18, 1896.

Application filed October 19, 1895. Serial No. 566,256. Term of patent 14 years.

To all whom it may concern:

Be it known that I, CHESTER B. ROSENBURGH, a citizen of the United States, residing at Rome, in the county of Oneida and State of New York, have invented and produced a new and original Design for Heads of Hame-Staples, of which the following is a specification, reference being had to the accompanying drawings, showing the same.

Figure 1 shows the front side elevation of the head portion of the hame-staple embodying my design in connection with the rivet portions of the staple in dotted lines. Fig. 2 shows a plan view of the same. Fig. 3 shows a perspective view of the same from the rear side.

The feature of my staple-head *a* is that the

head, as seen from directly in front or directly in the rear, is of substantially truncated conical shape, provided with an enlarged body *b*. ²⁰ This body portion *b* is enlarged, with the enlargement on the rear side of the staple. Partially surrounding the enlargement is a groove *c*.

What I claim is—

The design of the head of a hame-staple, substantially as shown and described.

In witness whereof I have affixed my signature in presence of two witnesses.

CHESTER B. ROSENBURGH.

Witnesses:

THEODORE J. MOWRY,
GEORGE S. KLERK.
